SLOW-TO-RELEASE RELAY

Ernest Frischknecht, East Orange, N. J., assignor
to The Teleregister Corporation, New York,
N. Y., a Corporation of Delaware

Application April 9, 1930. Serial No. 442,975

2 Claims. (Cl. 175—320)

This invention relates to improvements in slow-to-release relays.

Among the objects of this invention is the provision of means for causing a slow-to-release relay to pick up rapidly and to release substantially within the same minimum time period regardless of the number of impulses sent over the coil of the relay.

Other objects of this invention will appear from the description taken in connection with the drawing in which the figure shows a controlling means for a slow-to-release relay, and an apparatus in which such a relay may be used.

For purposes of disclosure the drawing shows a plurality of indicators A and B. The indicator A preferably comprises a ratchet wheel 1a, and an indicating pointer 2a secured to the ratchet wheel and which is adapted to travel over indicating numerals as shown. The ratchet wheel 1a is preferably operated by a pawl 3a actuated by a lever 4a operated by the operating magnet 5a. The ratchet wheel and pointer may be returned to normal by a spring 6a upon energization of a releasing magnet 7a which disengages the pawl 3a from the ratchet wheel 1a. The indicator B is of the same construction as the indicator A and corresponding parts of the indicator B are designated by the same numerals followed by small letters "b".

For the purpose of selecting one of these indicators for operation a selecting device, such as shown at S, may be provided. This device includes a ratchet wheel 1s and a circuit preparing arm 9 secured to the ratchet wheel and which is adapted to travel over an arcuate contact member 10 to prepare a circuit from this contact member to one of the fixed contacts 11 to which the energizing leads 12a and 12b of the operating magnets 5a and 5b of the indicators A and B are connected. This ratchet wheel is also operated by a pawl 3s which is actuated by an operating magnet 5s and which may be disengaged from the ratchet wheel by energization of a releasing magnet 7s. When the pawl is disengaged from the ratchet, the ratchet and pointer are returned to normal home position by a spring 6s.

Secured also to the ratchet wheel 8 is an arm 12 which when the ratchet wheel is moved out of home position releases the movable contact member 14 to apply ground to a line 13.

For the purpose of transmitting a series of impulses a key 15 is provided which connects battery over a constantly rotating interrupter 16 and over the coil of a relay 17 to ground. At the first impulse the relay 17 picks up and closes a circuit at its make contact 18 from ground over a normal make and break contact 19 of relay 20 to the coil of the operating magnet 5s of the selecting device S to battery and ground.

The first impulse over the interrupter causes energization of the operating magnet 5s which through the pawl 3s and ratchet 1s moves the arm 9 and the arm 12 ahead one step. As the arm 12 moves ahead one step it causes ground to be applied to the line 13 over the contact member 14.

Energization of the relay 17 also applies ground at its make contact 18a over a non-inductive resistance 21 and the coil of a slow-to-release relay 22 and over a normal break contact 23 of relay 24 to battery and ground. The coil of the slow-to-release relay 22 has a small number of turns which causes the operating current for the slow-to-release relay 22 to build up very rapidly. This causes the relay to be fast operating. The non-inductive resistance 21 is inserted in this circuit to prevent the relay 22 from drawing too high a current. This resistance does not affect the speed at which the relay 22 picks up. As the relay 22 picks up it applies ground at its make contact 25 to one terminal of the coil of relay 24, the other terminal of which is connected to battery and ground. As the relay 24 picks up it opens the short circuit for a non-inductive resistance 26 at its break contact 23 so that this resistance is thrown in, in series with the coil of the slow-to-release relay 22 and the non-inductive resistance 21. This causes the current over the coil of the slow-to-release relay 22 to drop quickly. Preferably, the resistance 26 is such as to cause this drop in current to be effected before the end of the first impulse over the coil of relay 22. The current drops below the operating requirements and to a value just sufficient to maintain the slow-to-release relay energized during the interval between impulses over the interrupter.

Operation of this control is as follows: As a single impulse or the first of a series of impulses is sent over the non-inductive resistance 21 and the coil of the slow-to-release relay 22 this relay will pick up very rapidly and because of its slow-to-release feature will remain operated until a subsequent impulse of a series of impulses is transmitted over its coil. The non-inductive resistance 26 thrown in by energization of the relay 24 will cut down the current over the coil of the relay 22 before the first impulse has ceased, to a minimum holding value and thus permits the slow-to-release relay to release within a certain time period regardless of the number of impulses sent over its coil. Energization of the slow-to-release relay 22, opens its break contact 27 which disconnects ground that is applied to the line 13 by the contact member 14 controlled by the arm 12 as it moves out of its released position and

prevents energization of the relay 20 as long as the slow-to-release relay 22 remains operated. Successive impulses over the interrupter 16 of the first series of impulses cause resultant impulses over the coil of the operating magnet 53 of the selecting device to adjust the arm 9 to select one of the indicators A, B, etc. for operation.

After the selecting impulses have ceased the slow-to-release relay 22 will deenergize and 10 break the circuit of the relay 24 which at its break contact 23 short-circuits the resistance 26. The slow-to-release relay 22 also applies ground over its break contact 27 to the coil of the relay 20 the other side of which is connected 15 to battery and ground. As this relay picks up it closes a holding circuit over its make contact 30 and at its make and break contact 19 it prepares a circuit over line 33 to the arcuate contact member 10 of the selecting device, 20 across the arm 9 to one of the fixed contacts 11, to the operating magnet 5a, 5b of the corresponding indicator A, B, etc. and to battery and ground.

When the key 15 is again depressed to actuate the selected indicator, impulses will be 25 generated by the interrupter 16 and will cause energization of the slow-to-release relay 22 as before which breaks the initial energizing circuit of the relay 20 at its break contact 27. The relay 17 will alternately close and open its make 30 contact 18 and send impulses over the operated make and break contact 19 of relay 20, the arcuate contact member 10, the arm 9 and one of the lines 12a, 12b, etc. to energize the operating magnet 5a, 5b, etc. of the selected indicator. Each impulse from the interrupter, therefore, causes the operating magnet of the selected 35 indicator to step the indicating pointer 2a, 2b, etc. of the indicator ahead one step.

As this series of impulses cease all the parts 40 in the drawing are restored to the position shown except the adjusted indicator and the selecting device. For the purpose of returning the selecting device to home position a key 31 may be provided which closes the circuit for the restoring magnet 7s which disengages the actuating pawl 3s from the ratchet 8 and permits the ratchet and arms 9 and 12 to return to normal under the influence of its spring 6s. As the ratchet moves into its home position its 45 arm 12 opens the contact member 14 and removes ground from the relay 20 which deenergizes. All the relays and the selecting device are now in the position shown in the drawing.

For the purpose of returning or restoring any 50 one of the indicators to zero before a new set-up is made keys 32a, 32b, etc. may be provided which when depressed will complete a circuit from ground to battery over the coil of the restoring magnet 7a, 7b, etc. of the respective indicator and over the key to ground. As the restoring magnet picks up it disengages the actuating pawl 3a, 3b, etc. from the ratchet 1a, 1b, etc. and permits the indicating pointer 2a, 2b, etc. to be returned to home position by the spring 6a, 6b, etc.

The circuit arrangement of this unit provides 55 for a constant release time of the slow-to-release relay 22 when operated by a series of pulses having a predetermined open and closed period. The operation of a slow-to-release relay over a pulsing circuit to ground does not provide for a constant release time of the relay until 60 several pulses have been transmitted, due to the

fact that the residual magnetism in the relay at the beginning of the second pulse is of a higher order of magnitude than the initial residual value and the maximum flux density at the end of the second pulse is therefore higher than the flux density at the end of the first pulse. The release time of the relay at the end of the second pulse, being a function of the flux density, is therefore greater than the release time at the end of the first pulse. This condition of an increase in the release time disappears after several successive pulses.

With the circuit arrangement shown, the operation of the slow-to-release relay 22 causes the relay 24 to operate and place a resistance in series with the winding of the slow release relay 22. The second pulse through this resistance produces a magnetizing force of reduced magnitude to compensate for the increased residual magnetism at the beginning of the second pulse. The value of this resistance is chosen with respect to the constants of the circuit so that the magnetic saturation at the end of the second and all succeeding pulses is approximately equal to the magnetic saturation of the relay at the end of the first pulse. This circuit arrangement provides for a constant release time of the relay 22 for any number of pulses.

While, for the purpose of disclosure, only one 105 of the uses of this invention has been shown, it is to be understood that its use is not to be limited to the particular kind of apparatus disclosed. By means of the control shown, I have provided a slow-to-release relay which picks up very rapidly and which releases within a certain 110 fixed time period regardless of the number of impulses that may be sent over the coil of the relay. This is important as it reduces the amount of time required between transmission of a series of selecting impulses and a series of 115 actuation impulses to a constant minimum. While the drawing shows keys for controlling the number of impulses sent to the selecting device and indicators this is merely by way of illustration. In actual practice the impulses may be produced by a movable tape and sensing devices such as are well known in the art, or by any other means by which impulses are sent in rapid succession automatically under the control of a set-up on a keyboard.

What I claim is:

1. The combination of a fast operating and slow-to-release relay, means for sending impulses over the coil of said relay, a non-inductive resistance in the circuit of said relay for limiting the current flow through said relay, a second non-inductive resistance, and means for throwing said second resistance into the circuit of said relay to reduce the value of the current over the coil of said relay to a holding value prior to the termination of the first impulse over the coil of said relay.

2. The combination of a slow-to-release relay constructed to pick up rapidly during the continuance of a short impulse over its coil, a non-inductive resistance, and means for throwing the non-inductive resistance in the circuit of the coil of said relay immediately after an operating current in the coil of the relay has been reached, said resistance being constructed to reduce the operating current to the value of a holding current prior to the termination of said impulse.
